MECHANISM FOR CONTROLLING PIANO-PLAYERS OR THE LIKE.

1,198,291.

Specification of Letters Patent. Patented Sept. 12, 1916.

Application filed May 6, 1912. Serial No. 695,511.

To all whom it may concern:

Be it known that I, EUGENE T. TURNER, a citizen of the United States, and a resident of the city, county, and State of New York, have invented new and useful Improvements in Mechanism for Controlling Piano-Players or the like, of which the following is a specification.

This invention aims to provide a certain improved mechanism for automatically controlling the position of an adjustable element of a piano player or other apparatus. The adjustment is effected by an undulating pressure tending to cause the adjustment in first one direction and then the other; or by a continuous flow of air under varying pressure; or by exerting two forces continuously in opposite directions and varying the relation between these forces as adjustment becomes necessary in one direction or the other; and is especially adapted, for example, to the maintaining of proper lateral registration or "tracking", of the music sheet of a piano player.

25 The accompanying drawing illustrates by way of example parts of a piano player embodying the invention; the single figure being a front elevation, partly in section, of such parts as are directly related to the improvement.

Referring to the drawing, A, B are side members of the fixed frame which carries the tracker board C, and usually carries also the rolls C' and C² for winding-on and for 35 rewinding the perforated music sheet D which passes over the tracker board. For the sake of clearness only one perforation D' is indicated, being in proper register with the aperture D² in the tracker board.

40 In order to maintain the proper lateral relation of the sheet with the tracker board it has been proposed to shift the tracker board or to shift the sheet by suitable adjustment of its rolls and otherwise; and the 45 present invention may be applied to any of these known methods of adjustment. But for the sake of simplicity of construction it is especially applicable to, and is illustrated in connection with, a movable tracker board.

50 The tracker board is shiftable laterally of the sheet, being provided with a pair of guide pins E and F at one end passing

through the side frame B and with a single pin G at the other end passing through the side frame A.

55 The adjusting mechanism includes a spiral spring H bearing against the side frame A and against a collar J which is mounted on the pin G and is adjustable in position thereon by means of a set screw K so as to 60 permit of manual variation of the force of the spring. This spring exerts a continuous force tending to shift the tracker board C to the left. For shifting it to the right I provide a pneumatic or bellows having a 65 fixed plate L attached to the side frame A and a movable plate M carrying a forwardly projecting arm N faced with a felt pad O which bears against the rounded end of the pin G. A suction is maintained 70 continuously in the bellows so that the arm N presses continuously against the end of the pin G and tends continuously to shift the tracker board to the right.

I purpose to maintain a continuous suction within the bellows and to merely vary the force of the suction within the pneumatic more or less as the necessity for adjustment is greater or less, thus maintaining in fact a continuous current of air with an 80 undulating pressure or suction for effecting the desired adjustments, in contradistinction to previous apparatus which only bring the adjusting forces into play intermittently. By this means an extremely nice 85 regulation is secured, the slightest departure from exact registration causing a corresponding increase or decrease in the pressure sufficient to correct the error. The adjustments and readjustments are always 90 very slight and the sheet is held in exact registration or substantially so at all times. In fact scarcely any movement of the 95 tracker bar can be seen. At the same time I have found that this continuous system permits of an extreme simplification of the apparatus, the valves and valve-operating diaphragms of the previous apparatus being unnecessary with the present system, and the pneumatic connections being reduced 100 to the simplest possible constructions.

In the mechanism illustrated the interior of the pneumatic or bellows L, M communicates through a small bleed hole P (which

is valveless and is continuously open and open always to a uniform extent) with a suction pipe Q communication with the usual vacuum chest or wind chest Q' in 5 which a suction is continuously maintained by any suitable mechanism; and the pneumatic communicates also through a small flexible tube R with a tracking-control aperture S in a block T which normally moves 10 with the tracker bar and constitutes practically a part thereof. At the moment of starting, the aperture S is entirely covered. But the suction quickly shifts the block T to the right and in the normal running position of the sheet its right hand edge 15 partially covers the aperture S. The quantity of air admitted through S is such that the suction within the pneumatic is just sufficient to balance the force of the spring H. 20 Now when the sheet shifts to the left a greater quantity of air is admitted through the aperture S, which constitutes practically an admission port to the pneumatic, the effective area of which is automatically adjustable, and the suction in the pneumatic is decreased and the spring H shifts the tracker bar to the left so as to maintain the normal position of the tracker bar relatively 25 to the sheet. If the edge of the sheet for any reason covers more than the exactly 30 correct area of the aperture S, the quantity of air admitted to the pneumatic is less than during exactly correct running, the suction is increased, and the tracker bar is shifted 35 to the right so as to correct the error.

In order to provide for sheets having wider and narrower margins I propose to make the part T in which the tracking-control aperture S is formed, longitudinally adjustable with respect to the part carrying the note apertures. For this purpose the block T is arranged to slide on the pins E and F and has a slot in which is located an adjustable nut U projecting slightly beyond 45 the face of the block and threaded upon a screw V which is fastened to the end of the note-carrying part of the bar and is adapted to pass freely through the block T. The nut U can then be turned easily with one's 50 finger while the first notes are being played. The nut U is beyond the edge of the sheet which is maintained in a practically fixed position relatively to the aperture S and the block T. If the sheet does not register exactly then the turning of the nut U in one 55 direction or another will cause the note portion of the tracker bar to shift slightly to the right or to the left until its apertures come exactly into alignment with those in 60 the sheet, after which the tracking-control is entirely automatic.

Though I have described with great particularity a certain embodiment of the invention, yet it is not to be understood therefrom that the invention is limited to the

particular embodiment disclosed. To persons skilled in the art it would be a simple matter to rearrange the passages for admitting or exhausting air from the pneumatic, to alter the arrangement and design of 70 spring and pneumatic, to substitute air pressure for suction and to make various other changes in the arrangement and combination of the parts without departing from the invention. 75

What I claim is—

1. Tracking-control mechanism for piano players or the like, including a part having an aperture which is partially open and partially covered by the music sheet in the normal position of the latter, a pneumatic of which said aperture constitutes an admission port which is varied in area as the sheet shifts laterally, and a suction device communicating with said pneumatic through a 80 bleed hole of fixed open area and unthrottled in all positions, a tracker board adapted to be moved in one direction by said pneumatic and a spring tending to move said board in the opposite direction, said 85 port being manually adjustable relatively to the tracker board.

2. In a piano player, in combination, a tracker board, means for passing a music sheet longitudinally over said tracker board, 90 a member bearing a fixed relation to said tracker board and provided with a single guide opening and tracking-control mechanism adapted to effect a relative lateral adjustment between said sheet and said tracker 95 board, and to hold them in such positions that said guide opening is normally partially covered by the sheet and partially open, said tracking-control mechanism including a spring exerting a continuous pressure to effect such adjustment in one direction and a single pneumatic having a movable plate M exerting an adjusting pressure in the opposite direction, said pneumatic being constantly in communication with said 100 guide opening and having a continuously open unthrottled bleed hole P, and a suction device communicating with said pneumatic through said bleed hole for maintaining the pressure on said movable plate M. 105

3. In a piano player, in combination, a tracker board, means for passing a music sheet longitudinally over said tracker board, a member bearing a fixed relation to said tracker board and provided with a single 110 guide opening and tracking-control mechanism adapted to effect a relative lateral adjustment between said sheet and said tracker board and to hold them in such positions that said guide opening is normally partially covered by the sheet and partially open, said tracking-control mechanism including a spring M bearing at one end against a fixed part of the apparatus and at 115 the other end against a movable member for 120 125 130

effecting such lateral adjustment in one direction, and a single pneumatic mounted upon a fixed part of the apparatus, having a movable plate M engaging said movable member to adjust it in the opposite direction, said pneumatic having an inlet communicating with said guide opening and having a bleed hole P constituting an exhaust port of constant open area unthrottled in all positions, and a suction device

communicating with said pneumatic through said bleed hole.

In witness whereof, I have hereunto signed my name in the presence of two subscribing witnesses.

EUGENE T. TURNEY.
